UNITED STATES PATENT OFFICE.

LUCIEN H. HUTCHINGS, OF McMINTONVILLE, OREGON.

CIGAR AND CIGARETTE HOLDER.

Application filed April 22, 1925. Serial No. 25,095.

This invention relates to a cigar and cigarette holder, and has for its object the production of a simple and efficient cigar and cigarette holder which will efficiently 5 and securely support a cigar or cigarette in engagement with the holder, so as to prevent the cigar or cigarette from falling from the holder.

Another object of this invention is the 10 production of a simple and efficient clamping means carried by a holder of the class described, which will efficiently grip the body of the cigarette or cigar, and hold the same in position upon the cigar or cigarette 15 holder, and at the same time permit a free draft through the cigar or cigarette without choking the same, as very often happens when one end of the cigar or cigarette is forced into the holder, which is now commonly used.

A further object of this invention is the 20 production of an efficient cigar and cigarette holder which is so constructed as to permit the cigar or cigarette to be readily released 25 from the holder, and at the same time efficiently support the cigar or cigarette in or upon the holder.

With these and other objects in view, this 30 invention consists of certain novel construction, combinations and arrangements of parts as will be hereinafter fully described and claimed.

In the drawings:

Figure 1 is a side elevation of the cigar 35 holder, showing a cigar in place.

Figure 2 is a top plan view of the structure, shown in Figure 1, the cigar being removed therefrom.

Figure 3 is a section taken on line 3—3 40 of Figure 2 looking in the direction of the arrow.

Figure 4 is a section taken on line 4—4 45 of Figure 2 looking in the direction of the arrow.

Figure 5 is an end elevation of the cigar 50 clamping means, the clamping ring being removed therefrom.

By referring to the drawings it will be 55 seen that 1 designates the body of the cigar holder which is of suitable construction, preferably of a tubular structure having a tapering mouth piece 2 of suitable design. The tubular body of the holder 1 is provided with a plurality of pairs of spaced lugs 3 near the outer end thereof, which lugs 3 60 constitute means for holding the cigar

clamping member against rotation and also preventing the clamping means from accidentally dropping from the holder, as will be obvious by considering Figures 1 and 2 60 of the drawings.

The cigar clamping means comprise an annular band 4 which is provided with a plurality of integral spring arms 5, which spring arms 5 are provided with inclined 65 ribs 6 upon their outer faces, as clearly illustrated in Figures 1 and 2 of the drawings, to permit the clamping ring 7 to firmly force the clamping jaws 8 into engagement with the cigar or cigarette, indicated by the 70 numeral 9. These jaws 8 are substantially concavo-convex shaped, so constructed as to fit snugly around the cigar or cigarette 9. These jaws 8 are carried by the outer ends 75 of the arms 5, and stop-lugs 10 are carried by the jaws 8 intermediate the ends thereof, and these lugs 10 constitute means for limiting the outward sliding movement of the clamping ring or band 7. By considering Figures 1 and 2 it will be seen that the 80 inner ends of the arms 5 fit snugly between the spaced lugs 3 and are in this manner held against rotary movement upon the body of the cigar holder 1.

It should be understood that the present 85 illustration has been used for demonstrating the mounting of a cigar in conjunction with the holder, although a cigarette may be employed without departing from the spirit of the invention, only a different 90 sized device being employed for this purpose. The construction of the two devices, that is to say the holder for the cigarette and the holder for the cigar being substantially identical in mechanical structure, it 95 has been thought only necessary to illustrate one form of the device.

By considering Figure 2 it will be seen that the band 4 is provided with a plurality of stop-lugs 11, located near the inner end 100 of the arms 5, and these lugs 11 will constitute means for preventing the dropping of the clamping ring 7 off of the cigar or cigarette holder 1. The lugs 3, by engaging the inner edges of the jaws 8, as shown in Figure 2, will prevent the dropping of the clamping device from the holder 1. The holder 1 is provided with the usual socket 112 indicated in dotted lines in Figure 1, for the purpose of receiving the inner end of a cigar or other smoking device such as a cigarette, cigar and the like.

The cigar or cigarette is placed in the holder as follows: One end of the cigar or cigarette is placed in the open end of a cigarette or cigar holder 1, the cigarette or cigar being slightly twisted while being so placed. The clamping means is then moved outwardly upon the holder 1 until the band 4 engages the inner edges of the lugs 3 of the holder 1. The clamping ring 7 is then forced outwardly over the inclined rib 6, thereby causing the clamping jaws 8 to firmly grip the outer face of the cigar or cigarette, the lugs 10 constituting a stop for limiting the outward movement of ring 7. The cigar or cigarette in this manner will be efficiently held in engagement with the holder, and will be prevented from accidentally dropping from the holder, due to the fact that the gripping means for the cigar or cigarette is arranged in spaced relation to the outer end of the body of the holder.

When it is desired to remove the cigarette or cigar, the clamping ring 7 may be moved inwardly toward the body 1 of the holder, thereby releasing the jaws 8 from the cigar or cigarette 9 and permitting the smoker to easily remove the cigar or cigarette from the holder. When the device is not in use, the band 4 is moved inwardly upon the holder 1 until the inner edges of the clamping jaws 8 engage the outer edges of the stop-lugs 3. The ring 7 may then be forced over the arm 5 so as to firmly clamp the arms in position and prevent the cigar or cigarette clamping means from moving longitudinally upon the holder 1. In this way the device may be conveniently carried in the pocket of the smoker without fear of bending or breaking the various parts such as the arms and clamping jaws. It should be further understood that should it be desired for any reason to remove the clamping means from the holder, the clamping ring 7 may be moved to the position shown in Figure 2 and the spring arms 5 may be forced outwardly over the lug 3 and the whole clamping means may then be pulled off of the holder by passing the same over the tapering end 2 of the holder 1.

The present cigar or cigarette holder is especially adapted for use by automobile drivers and other smokers who are working

upon machines or in factories where the fire hazard is a great risk. Through the medium of the clamping device associated with the holder, the cigar or cigarette will be firmly held in place, and will not be likely to drop from the holder as is the case with the holder now in common use.

It should be understood that certain detail changes in the mechanical structure may be employed without departing from the spirit of the invention, so long as these changes fall within the scope of the appended claims.

Having described the invention, what is claimed is:

1. A holder of the class described comprising a body-portion, substantially cylindrical in form, and having spaced lugs formed near the outer end thereof, a clamping means comprising a band slidably mounted upon said body portion, said band provided with a plurality of clamping arms fitting between said lugs, whereby said band will be held against rotary movement upon said body-portion, clamping jaws carried by the outer ends of said arms, and means slidably mounted upon said arms for firmly clamping said jaws in engagement with a smoking article and holding the smoking article in firm engagement with said body-portion.

2. A holder of the class described, comprising a body-portion, said body-portion constituting a mouth piece, lugs formed near the outer end of said body-portion, a clamping member comprising a band fitting around said body-portion, clamping arms carried by said band and fitting between said lugs, whereby said band will be held against rotary movement upon said body-portion, clamping jaws carried by the outer ends of said arms, an inclined rib formed upon each arm, a clamping ring slidably mounted upon said arms and adapted to cooperate with said ribs for firmly forcing said jaws into engagement with a smoking article, whereby the smoking article will be efficiently supported in conjunction with said body portion, and means carried by said band for limiting the movement of said clamping ring in one direction.

In testimony whereof I affix my signature.
LUCIEN H. HUTCHINGS.
